Inventor
Rodney Thomas Bunn
By Clarence A. O'Brien
Attorney

UNITED STATES PATENT OFFICE.

RODNEY THOMAS BUNN, OF DANVILLE, VIRGINIA.

GALLEY-SLUG ADJUSTER.

Application filed September 18, 1926. Serial No. 136,319.

This invention relates to an improved device in the form of an attachment adapted to be associated with a linotype machine.

The invention has more particular reference to an efficient and automatically operable device of simple and inexpensive construction which is applied to the machine at a point to cooperate with the leads for insuring straight feeding of the same to facilitate handling.

The particular construction of the device will become apparent from the following description and the drawings—

In the drawings—

Figure 1 is an edge view showing the device applied to the parts of the machine with which it cooperates,

Fig. 2 is a detail perspective view of the device removed from the machine.

In the drawings, the reference character 1 designates generally the machine which is of customary construction and which includes the customary lead guide and receiving tray, etc. These parts are of conventional form and will be plainly apparent to linotype operators. Consequently, a more specific description of the machine is thought unnecessary.

The attachment per se is designated generally by the reference character 2 and the same comprises a check 3 in the form of an elongated flat metal bar which is preferably tapered on its inner side at its lower end as indicated at 4. The upper end is pivotally connected as at 5 to a hanger block 6, and this block is provided with an elongated slot 7 for passage of a fastening screw 8 by means of which it is connected to the machine to cooperate with the lead guide.

It will be noticed that the block is of bifurcated formation and that the upper end of the check bar is located between the furcations. In fact, a portion projects above the pivotal connection 5 and the furcations, and this portion is provided with a stud 9 surrounded by a coiled spring 10 which bears against the machine as shown in Fig. 1.

It is plain that when the device is in place on the machine, in the proper position, it will cooperate with the bunched type to insure straight downward feeding into the re-

ceiving tray. It is thought that this galley slug adjuster will be of great benefit in that it will aid the printer in handling the type. It is automatically operable and is not likely to get out of order, it being exceptionally simple in construction, and being quite inexpensive to manufacture.

Moreover, it is advantageous in that it is in the form of an attachment, which may be applied without requiring alterations to the existing parts of the machine. These and other advantages and features of the invention have doubtless been made apparent from the description and drawings. Consequently, a more lengthy description is thought unnecessary.

Minor changes coming within the field of invention claimed may be resorted to if desired.

Having thus described my invention, what I claim as new is—

1. A galley slug adjuster comprising a hanger and attaching block provided adjacent its top with a horizontally elongated opening for passage of an attaching bolt and having its lower portion bifurcated, a depending bar having its upper end located between the furcations on said blocks, a pivot pin connecting said bar with said furcations, the pivot pin being located at a point downwardly of the upper end of said bar, an inwardly extending stud carried by the upper end of the bar, the stud being located above the pivotal connection, the lower end of the said bar being beveled on its inner side, and a coiled spring surrounding said stud.

2. A galley slug adjuster comprising a block, a bar depending from said block and pivotally connected at its upper end to said block, the pivotal connection between the block and the bar being disposed downwardly with respect to the upper end of said bar, the lower end of said bar being beveled outwardly on its inner side, an inwardly extending stud carried by the bar and supported on the bar at a point spaced above said pivotal connection, and a spring surrounding said stud.

In testimony whereof I affix my signature.

RODNEY T. BUNN.
